UNITED STATES PATENT OFFICE.

ROBERT ROETHLISBERGER, OF COLUMBUS GROVE, OHIO.

HOG-RING.

1,372,247.

Specification of Letters Patent. Patented Mar. 22, 1921.

Application filed November 16, 1920. Serial No. 424,439.

To all whom it may concern:

Be it known that I, ROBERT ROETHLISBERGER, a citizen of the United States, residing at Columbus Grove, in the county of 5 Putnam and State of Ohio, have invented a new and useful Hog-Ring, of which the following is a specification.

This invention relates to nose rings to be secured to the noses of hogs to prevent the 10 hogs wearing the same, from rooting.

The primary object of the invention is to provide a nose ring having novel means to engage roots or other obstacles to move the ring in the nose, causing pain to the 15 animal.

A still further object of the invention is to provide means for securing the ring to the nose in a manner to eliminate any possibility of the same becoming displaced, when 20 the animal wearing the same is rooting.

With the foregoing and other objects in view which will appear as the description proceeds, the invention resides in the combination and arrangement of parts and in the 25 details of construction hereinafter described and claimed, it being understood that changes in the precise embodiment of the invention herein disclosed, may be made within the scope of what is claimed, without departing from the spirit of the invention.

Referring to the drawing:—

Figure 1 illustrates a perspective view of the nose ring constructed in accordance with the present invention, and showing the same 35 as applied.

Fig. 2 illustrates a perspective view of the device.

Referring to the drawing in detail, the device is shown as including oppositely disposed sections 5 and 6 respectively, each section comprising laterally extending arms, 40 extending in opposite directions.

The arms forming a part of the section 5 are curved downwardly as at 7 to conform 45 to the curvature of a hog's nose at the upper portion thereof, the arms also providing means to accommodate securing rings, by means of which the device is secured.

The section 6 has one arm extending downwardly as at 8, to overlie the forward 50 portion of the snout, the lower end thereof terminating at a point adjacent to the mouth of the animal.

The opposite arm of the section 6 is relatively straight, throughout a portion of its 55 length, one end thereof extending at an angle toward the opposed arm of the section to provide a hook portion 9 adapted to engage roots or similar obstructions to cause the device to move on the snout of the 60 animal.

From the foregoing it is obvious that the device is constructed to closely fit over the snout of an animal, the arms of the section 5 accommodating the rings 10 which are 65 positioned in the flesh of the animal's snout to eliminate any possibility of the device becoming displaced.

Having thus described the invention, what is claimed as new is:—

A nose ring comprising a body portion 70 formed of sheet metal and including opposed sections, each of said sections including arms, the arms of one section being curved downwardly to conform to the curvature of the nose of an animal, the ends thereof adapted to engage the side edges of the animal's nose, one of the arms of the opposite section being curved downwardly 75 to overlie the forward portion of an animal's nose, one of the arms of the latter section overlying the upper portion of the animal's nose and having a hook portion formed at the end thereof, and ring members 80 embracing the downwardly curved arms for securing the nose ring.

In testimony that I claim the foregoing as my own, I have hereto affixed my signature in the presence of two witnesses.

ROBERT ROETHLISBERGER.
